UNITED STATES PATENT OFFICE

ROBERT SIMON, OF CHICAGO, ILLINOIS

LOCKING DOOR HANDLE

Application filed March 29, 1929. Serial No. 350,928.

The present invention relates to improvements in locking door handles, and particularly to a door handle, for operating a latch in a vehicle door, having novel means therein for rendering said handle inoperative relative to the latch.

The invention has for an object the provision of a novel door handle having a key-operated lock mounted therein for actuating means to permit free rotation of said handle when in locked position.

Another object of the invention resides in the provision of a novel locking door handle requiring but few parts and which is, therefore, capable of being manufactured at low cost.

Another object of the invention is to provide a novel locking door handle which is positive in operation and which, when locked, cannot be rendered operative by unauthorized tampering therewith.

Another object of the invention resides in a provision of a locking door handle having novel means therein for preventing its withdrawal from the door.

These and such other objects of the invention as will be more readily understood from a perusal of the following specification, are attained by providing a novel locking door handle having key-operated means therein to actuate means for rendering the handle inoperative, said handle being free to rotate without actuating the latch, associated therewith, when locked. The provision of the novel means for permitting the handle to rotate eliminates the possibility of the latch being forced by unauthorized persons.

In the accompanying drawings are shown exemplary embodiments of the present invention, in which:

Fig. 1 is a fragmentary elevational view of the body and door of a vehicle, showing the improved locking door handle mounted therein.

Fig. 2 is an enlarged vertical central sectional view through the door of the vehicle showing the novel locking handle in operative engagement with the usual latch means mounted on said door.

Fig. 3 is a horizontal sectional plan view

through the door, the latch, and the improved door handle, taken on line 3-3 of Fig. 2.

Fig. 4 is a transverse sectional view through the shank of the locking door handle, taken on line 4-4 of Fig. 2.

Fig. 5 is an enlarged vertical central sectional view of the end of shank, showing the means for retaining it in engagement with the latch actuating means, taken on line 5-5 of Fig. 3.

Fig. 6 is a perspective view of the collar or sleeve employed in the locking door handle, but showing a modified form of construction

Fig. 7 is a vertical sectional elevational view of a portion of a locking door handle showing a modified form of construction.

The improved locking door handle preferably comprises a tubular stem 11 having a cross bar 12 rigidly secured on one end thereof to form a handle. Rigidly secured within the stem 11 and extending beyond the end thereof is a tubular stem or housing 13 of small diameter having a pair of parallel arms or extensions 14 extending therefrom. A shank 15, preferably square in cross section, is rigidly mounted between the spaced parallel arms 14, and extends beyond the end of said arms. A centrally located recess 16 is provided on the outer end of the shank 15 which is adapted to receive therein the reduced end 17 of a shank extension 18. This reduced portion 17 is provided with an annular flange near its end to permit the two shank members 15 and 18 to be rotatably secured together by a retaining pin 19.

The locking door handle assembly thus provided is inserted into a hole 21 provided therefore in the vehicle door frame 22. A suitable bearing is provided for the handle by the provision of an escutcheon plate 23 which encircles the tubular stem 13 and is secured to the door frame 22 by means of screws 24.

The rotatable extension 18 on the shank 15 is adapted to engage in a recess provided in a latch actuating means 25 mounted for rotation in the latch housing 26, which hous-

ing is carried on the inner side of the vehicle door, as shown.

The latch mechanism mounted within this housing is of the usual construction, the latch actuating means 25 having portion thereof engaging in a latch 27, whereby upon actuation of the former said latch is withdrawn from a keeper plate 28 mounted in the vehicle body 29. Suitable means, such as a coil spring 31, is provided within the housing 26 to normally urge the latch 27 into engagement with the keeper plate 28 to retain the door in closed position.

As previously mentioned, the extension 18 is rotatably mounted on the end of the square shank 15, however, novel means is provided to effect a rigid connection between these two members. This means comprises collar or sleeve 32 slidably mounted on the square shank 15, said collar normally extending beyond the end of the shank 15 and over a portion of the extension 18. It can readily be seen that when the collar 32 is in its extended position, as shown in Figs. 2 and 3, manipulation of the locking door handle 12 operates the latch actuating means 25 thereby withdrawing the latch 27 from the keeper plate 28.

To lock the vehicle door the locking door handle is rendered inoperative by withdrawal of the sleeve 32 from engagement with the rotatable extension 18. To this end key-operated means 33, of any suitable construction, is securely mounted within the tubular stem 13, said key-operated means having an eccentric 34 on the innermost end of its rotatable barrel portion 35. Pivotally mounted between the arms 14 and having a portion thereof extend outwardly beyond one side of said arms, is a lever arm 36, having operative engagement with the eccentric 34. The lever arm 36 and the sleeve 32 are operatively connected by a link 37, said link preferably comprising a substantially U-shaped wire frame having its bent end pivotally secured in the link 37 and having its free ends bent inwardly to engage in suitable sockets provided therefor in opposite sides of the sleeve 32.

Upon manipulation of the key-operated means to lock the door, the lever arm 36 is moved on its pivot, due to its engagement with the eccentric 34; to the position shown in dotted lines in Fig. 3, said movement withdrawing the sleeve 32 from engagement with the rotatable shank portion 18. With the parts of the door locking handle in this position, said handle may be freely rotated without actuating the latch 27. To render the door locking handle operative the key-operated means is further manipulated to move the lever arm 36 to its former position thereby again sliding the sleeve 32 over the rotatable shank portion 18.

To insure proper positioning of the door

handle 12 when same is rendered operative, suitable pins 39 are provided on the extension 18 adapted to be engaged by cooperating slots 41 provided therefor on the forward edge of the sleeve 32. These pins also insure the rigid connection between two members, as a considerable amount of strain is taken up thereby, to prevent the squared opening within the sleeve 32 from becoming rounded.

To prevent withdrawal of the locking door handle 12 from the vehicle door, automatic retaining means is provided in the shank extension 18 for engaging the latch actuating means 24. This means preferably comprises a pair of pawls 42, which pawls are pivotally mounted in suitable recesses provided therefor in said shank portion. Hook portions 43 are provided on the outer ends of the pawls 42 and a compression spring 44 is interposed therebetween, an opening being provided therefor in the body of said shank.

The hook portions 43 are rounded on their edges to permit free insertion of the shank extension 18 into the opening in the latch actuating means 24. Upon the insertion of the shank extension into the latch actuating means the pawls 42 are urged outwardly by the spring 44, and the hooked portions 43 of said pawls engage the rear face of said latch actuating means. Additional means for retaining the locking handle in position is provided for by a collar 45 rigidly mounted on the tubular stem 13, and a compression spring 46 is interposed between said collar 45 and the escutcheon plate 23 to provide a yielding limit therefor.

In Fig. 6 a modified form of sleeve construction is shown wherein an extension 47 is provided on the rear edge of one wall of said sleeve. The end of this extension is rounded and bent at right angles thereto, as at 48, for engaging in the lever arm 36.

In the modified form of the invention, as shown in Fig. 7, the barrel 35a of the key-operated means 33a is provided with worm thread 49. A collar 51 is slidably mounted within the tubular stem 13a, of the handle, and is provided with internal threads for cooperation with the threads on the barrel 35a. Slots 52 are provided in the wall of the tubular stem 13a to permit the oppositely disposed pintle extensions 53, of the collar 51, to extend therethrough, each pintle extension having a link 54 pivotally mounted thereon, which links have their opposite ends engaging in the collar 32a.

The operation of a door locking handle of this character is as follows; to lock the vehicle door, the key-operated means 33a, is rotated drawing the collar 51 rearwardly to slide the collar or sleeve 32a out of engagement with the rotatable shank portion 18a thus rendering the handle inoperative. To unlock the vehicle door the key-operated

means is turned in the reverse direction to urge the collar 51 and the sleeve 32a forwardly to their former position.

Construction of the door locking handles of the types disclosed is extremely simple, they employing but a few parts which may readily be assembled thereby materially decreasing the cost of manufacture. The novel means provided for retaining the shank extension 18 in engagement with the latch actuating means affords a simple and positive connection, inasmuch as in most methods now commonly employed the handle is liable to become disengaged therefrom due to vibration of the vehicle loosening the retaining means. When in operative position the door handle is rigidly connected with the latch operating means and when in locked position said handle is free to rotate, thus preventing the latch from being forcibly actuated.

It is to be understood that while only exemplary forms of the present invention have been disclosed in the foregoing description and illustrated in the accompanying drawings, said invention is capable of embodying modifications in detail structure without departing from the spirit of the invention or the scope of the appended claims.

I claim:

1. A latch operating handle comprising, a tubular stem having a pair of extended arms rigid therewith; a shank rigidly secured between said arms having a rotatable extension on the end thereof; latch actuating means engaged by said extension; a collar slidably mounted on said shank; a lever arm pivotally mounted between said arms having an operative connection with said collar; and key-operated means for moving said lever arm to slide the collar into engagement with said rotatable extension to render the latter non-rotatable relative to the shank.

2. A door handle rotatably mounted in a door and adapted to receive a key-operated mechanism comprising, a stem having a shank rigidly secured therein; a rotatable extension on said shank; means for actuating a latch engaged by said extension; and means slidably mounted on said shank portion actuated by said key-operated mechanism for engaging the rotatable extension to permit actuation of the latch upon manipulation of the door handle.

3. A door handle having a key-operated mechanism mounted therein, adapted to be rotatably mounted in a door, comprising, in combination, a stem having a shank rigidly secured therein; a rotatable extension on said shank; means for actuating a latch engaged by said extension, and means on said extension for engaging in the latch actuating means to prevent withdrawal of the door handle from the door.

4. A door handle having a key-operated mechanism mounted therein rotatably

mounted in a door; comprising, a stem having a shank rigidly secured therein; a rotatable extension on said shank; means for actuating a latch engaged by said extension, and yielding means in said extension for engaging the latch actuating means to prevent withdrawal of the handle from the door.

5. The combination with a door having latch means mounted on the inside face thereof and having an opening extending therethrough to receive a door handle, said door handle having a shank for engaging said latch means; and means pivotally mounted in said shank yieldingly engaging said latch means to prevent withdrawal of the handle from the door.

6. A door handle rotatably mounted in a door, comprising, a stem having key-operated means mounted therein; a lever arm pivotally mounted in said stem for actuation by said key-operated means; a shank carried by said stem having a rotatable extension adapted to engage in latch actuating means mounted in said door; and means operatively associated with the lever arm to render the rotatable extension rigid to permit actuation of the latch actuating means upon manipulation of the door handle.

7. The combination with a door having latch means mounted on the inside face thereof and having an opening extending therethrough to receive a door handle, said door handle having a shank for engaging in said latch means; means pivotally mounted in said shank yieldingly engaging said latch means to prevent withdrawal of the handle from the door; and key operated means in said handle to permit manipulation of the latter without operating said latch means.

In testimony whereof I affix my signature at 10 South La Salle Street, Chicago, Illinois.

ROBERT SIMON.
